UNITED STATES PATENT OFFICE.

ADOLPH BIERMAN, OF NEW YORK, N. Y.

DESIGN FOR IMITATION FUR TRIMMING.

SPECIFICATION forming part of Design No. 30,127, dated January 31, 1899.

Application filed February 23, 1897. Serial No. 624,726. Term of patent 3½ years.

To all whom it may concern:

Be it known that I, ADOLPH BIERMAN, a subject of the Emperor of Germany, residing in the city, county, and State of New York, have invented and produced a new and original Design for Imitation Fur Trimmings, of which the following is a specification.

In the drawings forming part of this specification, Figure 1 is a front elevation, and Fig. 2 a side elevation, of an article made in accordance with my design.

My invention resides in the shape and configuration of the article.

At 1 is a backing-piece rectangular in form, and disposed sinuously—that is to say, it is crimped or fluted transversely, forming the transverse corrugations 2. Extending radially from the outer surface of the backing-piece are tufts or piles 3 of imitation fur, each tuft being substantially the same length, the top tuft overlapping the one immediately below it, each tuft being slightly thinned out at the points 4 and secured in transverse series on the face of the backing. Besides extending radially from the plane of the face of the backing, as indicated in Fig. 1, within

the area of the backing (indicated in dotted lines) the tufts also extend outwardly and radially from the edge of the backing, as at 5, Fig. 1, and gradually come together and terminate in a blunt point below the end of the backing, as at 6, at which point the tufts gradually thin out. It will be noticed that the tufts for their entire length partake of the same crimping or corrugating effect as has 35 the backing-piece, as indicated by the shaded lines 7 in Fig. 1.

In side elevation the aggregated tufts begin thin at the top, then increase in thickness, and gradually thin out toward the end, while 40 in front elevation the contour of the sides presents an ovate shape.

Having described my invention, I claim—

The design for an artificial fur trimming, substantially as herein shown and described. 45
Signed in the city, county, and State of New York this 20th day of February, 1897.

ADOLPH BIERMAN.
